UNITED STATES PATENT OFFICE.

EDWIN L. WIEGAND, OF DORMONT BOROUGH, PENNSYLVANIA.

ELECTRICAL HEATING ELEMENT.

Application filed August 31, 1923. Serial No. 660,294.

This invention relates to new and useful improvements in electrical heating elements of the type wherein the resistor is enveloped in refractory material. More specifically the invention may be stated to consist of a novel class of heating elements and a process for making the same wherein the resistor is enveloped in a sheet metal casing and insulated therefrom by a compact mass 10 of refractory material.

I am aware that a resistor in the form of a single straight conductor has been enclosed in a metal sheath and insulated therefrom by finely divided refractory material, 15 such a construction being commonly referred to as sheathed wire. This type of heating element has the disadvantage that it is very difficult and expensive to manufacture. During the drawing process, the 20 resistor wire develops irregularities in cross section and hence the life of the element is greatly shortened. The refractory material also becomes unevenly displaced, and the resistor is not located centrally with respect 25 to the outer metal casing and therefore the insulation is impaired. This sheath wire is capable of being bent and massed into spiral and serpentine forms of heating elements with some degree of success, although 30 it will be obvious that there is a double wall of the refractory material and metal casing between each convolution or adjacent length of the spiral or serpentine type of heating element. This double wall requires 35 space that might well be utilized by a more massive resistor to greatly increase the efficiency of the element, as it is well known that there is a definite relation between the area of the space available for the element 40 and the cross section of the resistor which can be employed for a given voltage and wattage, and there is also a definite relation between the cross section of the resistor and the durability of the element at a given 45 resistor temperature.

A further serious object to sheathed wire is that the single strand resistor is disposed along a line parallel to its support for a distance, such, that the differences in 50 expansion between the resistor and support set up strains on the resistor which cause failure.

I am also aware that heating elements, known as tubular elements, have been 55 formed by introducing a long spiral resistor

into a metal tube and insulating it from the tube with finely divided refractory material. This type of heating element is also very difficult and expensive to manufacture as it is necessary to introduce the spiral resistor and insulating material into the end 60 of the tube. Due to the fact that the element is in rod form, the ratio of emissivity to cross section is comparatively low and the heat diffusion is not as good as with 65 thin, flat types of elements. The spiral form of resistor involves a central core of refractory material which requires useful space and material, and the core absorbs heat from the resistor. Such units necessitate a high 70 resistor temperature for a given rate of energy input which tends to shorten their life and to limit the possible safe rate of energy input. While this type of element 75 may be massed into spiral or serpentine shapes, it is open to the same objection as stated in connection with sheathed wire, namely, a double wall of refractory material and metal casing is interposed between adjacent convolutions or lengths of the resistor. 80

A heating element in the form of a solid cylinder has also been made. This type of element is formed by first coiling the resistor on a rigid rod then inserting the same into a metal tube and filling the intervening space between the tube and resistor with finely divided refractory material. 85

This type of element cannot be shaped, and it emits heat from the outer surface only. It will be obvious that many of the 90 disadvantages previously set forth also apply to this type of heating element.

A fourth type of heating element is produced by winding the resistor on a mica core, or other core having an insulating film 95 applied thereto, then applying a layer of mica insulation thereabout, and finally sheathing the element in metal. This type of insulation is not truly refractory and hence the element will not stand thermal 100 abuse. The resistor is not in intimate contact with a heat receiving material over its entire surface and is susceptible to oxidation. Inasmuch as such fragile material as mica is used for insulation, it will at 105 once be apparent that these heating elements cannot be bent or shaped without great risk of damage to the insulation which would result in ultimate break down, the chief objection to this type of heating 110

unit being the inability of mica or other less refractory insulation to continuously withstand high temperatures, as well as the lack of density of the element or conductive intimacy between the resistor, insulation and support.

In so far as I am aware, a relatively thin and light weight heating element consisting of a resistor enveloped in a highly compacted mass of refractory material and having a sheet metal casing applied thereto, has never been successfully produced, and it is the general object of the present invention to provide a novel class of heating elements and a process for making the same wherein the resistor is completely enveloped in a highly compacted mass of refractory material, with the whole contained in a sheet metal casing, and the elements in each instance having relatively thin walls and large ratio of surface area to mass, so that maximum heat emissively is obtainable.

Another object is to provide a novel class of heating elements which by nature of their construction and relatively thin walls and cross section may be easily shaped to lie in intimate contact with the object to be heated and thereby obtain minimum resistance to transfer of heat from the element to the object.

Another object is to provide a class of heating elements of the aforesaid character which may be entirely enclosed in an imperforate sheet metal casing and thus afford ample protection for the resistor against moisture or other foreign matter, or where conditions permit may be enclosed in a partially or wholly perforated metal casing so that the casing and refractory material will form an interlock with each other and add to the rigidity of the elements to prevent warping and also maintain the integrity of the element and facilitate the displacement of the metal casing during the forming or shaping operation hereinafter referred to.

A still further object is to provide a group of heating elements which may be adapted, by forming or shaping when necessary, to numerous uses, and which shall be simple in construction, inexpensive to manufacture and which shall be highly efficient and durable in operation.

With these and other objects in view, the invention consists in the various novel features of construction and arrangement or combination, all of which will be fully described hereinafter and pointed out in the appended claims.

In the accompanying drawings wherein I have shown various illustrative embodiments of my invention but without intent to limit myself thereto, Fig. 1 is a plan view of a strip from an element with parts broken away to more clearly show the construction; Fig. 2 is a side elevation thereof with parts

broken away; Fig. 3 is an enlarged transverse section of the element shown in Figs. 1 and 2; Fig. 4 is an enlarged fragmentary view of a slightly modified form of element; Fig. 5 is a fragmentary plan view of a perforated cover employed in some instances; Figs. 6 and 7 are side elevations of an element such as shown in Figs. 1 and 2 and showing the same bent into two different forms; Fig. 8 is a plan view of an irregularly shaped plate illustrating another form of my invention; Fig. 9 is a sectional view taken on the line 9—9 of Fig. 8; Fig. 10 is a side elevation of the plate showing the same bent into a suitable shape; Fig. 11 is a plan view of a heating element in the form of a disk provided with a perforated casing; Fig. 12 is a sectional view through a disk which has been cupped; Fig. 13 is a plan view of a disk provided with an imperforate casing; Fig. 14 is a plan view with parts broken away of ring type of element; Fig. 15 is a sectional view taken on the line 15—15 of Fig. 14; Figs. 16, 17 and 18 are plan views of modified forms of heating elements; Fig. 19 is a perspective view, with parts broken away, of a hollow cylindrical type of heating element; Fig. 20 is a longitudinal view through a cylindrical element; and Figs. 21—25 are sectional views showing the various steps in my process for forming the elements.

Referring particularly to Figs. 1—7 inclusive, wherein I have shown a strip type of heating element, 1 denotes the resistor which is preferably bent into serpentine form from a suitable resistance ribbon. This resistor is molded in and completely enveloped by a hard and compact mass of cement like refractory material 2 which not only supports the ribbon at all points, due to its intimate contact therewith, but also prevents oxidation of the resistor. Each end of the resistor is connected to a terminal 3 which may be of any suitable type but preferably similar to that disclosed in my co-pending application Serial No. 555,870, filed April 21, 1922. These terminals are each provided with an insulating washer 4 which prevent contact of the terminals with a sheet metal casing composed of a channel receptacle 5 and a cover plate 6 which completely surround the refractory material. The side edges 7 of the receptacle are deflected over the cover plate as clearly shown in Figs. 1 and 3, and the ends of the casing, beyond the terminals 3 are flattened as indicated at 8 and are provided with apertures 9 so that the element may be conveniently supported on a frame or fastened to an object to be heated. If desired the seam formed by deflecting the side edges 7 over the cover plate may be welded, although for ordinary conditions, folding over the edges under high pressure will prove sufficient.

In some instances where it is unnecessary to provide a tight seal for the insulating material, I perforate a portion of the metal casing, as for example the cover plate 11 as shown in Fig. 5. During the folding and pressing of the side edges of the casing, the refractory mass will be forced into the perforations and thereby serve to bond the refractory material and casing together.

10 A strip heating element of this general character is very thin, light in weight, and permits maximum transfer of heat from the resistor to the object to be heated. The resistor is completely enveloped in a compact mass of refractory material and hence is supported at all points and is completely protected against oxidation. These strips may be readily bent to various shapes to meet the particular requirements. In Fig. 4 I have shown the element bent to assume an arcuate cross section while in Figs 6 and 7 I have shown the element bent into U-shaped form and circular form respectively. The U-shaped form is suitable for application to molds and similar uses, while the circular form may be conveniently applied to any circular object, as for example, a pipe or water heater. A bolt 12 engaged through apertures 9 serves to retain the element in position on the object.

In Figs. 8-13 inclusive, I have shown a second group of heating elements which are characterized by having relatively large areas and very thin cross sections. These elements are intended to replace the spiral and serpentine types of heating elements which are formed by bending and massing sheathed wire or similar straight elements. Figs. 8 and 9 show an example of a polygonal type of heating element consisting of a sheet metal receptacle 13 which is provided with a perforated cover 14 so that the refractory material 15 will interlock therewith. This type of element as well as those previously described may be bent into various shapes, without damage to the element or any parts thereof, and as an example, I have shown one side thereof bent over at right angles in Fig. 10. If desired the other side may also be bent as indicated in dotted lines in this figure.

In Figs. 11 and 12 I have shown a circular type of heating element which has the entire casing 16 perforated so that the refractory material and casing are bonded on all surfaces. This type of element may be cupped as shown in Fig. 12 so that the element will contact at all points with a vessel or other object having a semi-spherical surface. The perforated casing permits the metal to be evenly distributed during the bending and hence prevents buckling.

In Fig. 13 I have shown a circular type of heating element having an imperforate casing 17 and which is adapted for use on a

flat surface, or as an insert. Because of the relative thinness of this unit and the lack of perforations to form a bond between the refractory material and casing, I preferably insert therethrough a plurality of eyelets 18 which effectively tie the casing and refractory material together and prevent the casing walls from buckling.

In Fig. 14 I have shown a ring type of heating element in which the receptacle 20 of the casing is in the form of a circular channel. The resistor 21 is completely enveloped in a compact mass of refractory material as in the types previously described. A circular metal cover 22 is laid on top of the refractory material and the inner and outer peripheral edges of the receptacle 20 are deflected over the washer as shown in Fig. 15. This type of heating element is somewhat similar to that shown in Fig. 7 except that the casing is previously formed into a circle about its edge. An element such as shown in Fig. 14 is capable of assuming various shapes as for example the triangular form 25 shown in Fig. 16, or the angular or V-shaped form 26 shown in Fig. 17, or a modified triangular form 27 such as shown in Fig. 18. These forms adapt themselves to various requirements. The form shown in Fig. 18 for example being suited particularly for electric irons.

In Figs. 19 and 20 I have shown a hollow cylindrical type of heating element which is particularly useful for application to pipes or cylinders which are to be heated. This element may be conveniently formed by providing a circumferentially wound resistor completely enveloped in a compact mass of refractory material and then enclosing the same in a sheet metal casing comprising an outer metal tube 29 having turned peripheral edges 30 and an inner metal tube 31 having out-turned peripheral edges 32. This type of element emits heat from its inner and outer cylindrical surfaces and also from the ends and hence is very efficient.

In Figs. 21-25 inclusive, I have illustrated the various steps employed in my process for forming the heating elements herein disclosed. In carrying out this process I first provide a sheet metal receptacle 35 and fill the same with a mass of receptive refractory material 36. I next insert into this refractory material, a previously formed resistor 37 and then completely fill the receptacle with refractory material. The partially formed element is now subjected to a preliminary compacting operation, as indicated in Fig. 22, to insure intimate contact of the refractory material with the resistor and the receptacle. In the case of heating elements which are to be provided with an imperforate casing I next dry the partially formed element and then apply a cover plate and either simultaneously or in separate opera-

tions deflect the edges of the receptacle over the cover plate and heavily compress the element.

- 5 In the case of elements which are to be formed with a perforated casing, I apply a perforated cover 38 before or after the preliminary compacting operation and then deflect the edges of the receptacle over the cover to close the casing as shown in Fig. 23.
- 10 The element is then bent approximately to the desired form as shown in Fig. 24 and subjected to a final pressing operation as shown in Fig. 25, the latter operation causing the plastic refractory material to fill 15 the perforations in the casing and form a bond therewith. The heating element is dried and baked either by an external source of heat or by energizing the resistor.

20 While so far as the present invention is concerned, I do not limit myself to any particular kind or refractory insulating material, one class found especially suitable for the purpose is composed of magnesium or aluminum oxide or zirconium silicate, either 25 individually where possible or a compound of them, together when desirable with a binding material such as clay, to give the necessary plasticity during fabrication and to effect homogeneity in the final product.

30 The resistor element may be enveloped in the refractory insulating material in accordance with my Patent Number 1,136,076, issued April 20, 1915 entitled "Process of producing electrical heating devices" or in accordance with my Patent Number 1,398,- 35 410, issued November 29, 1921 entitled "Embedding process."

40 Manifestly the present invention greatly facilitates the production of sheathed, embedded, electrical heating elements by providing a comparatively shallow open sided receptacle into which the granular refractory insulating material and the resistor may be properly placed before the receptacle 45 is closed, thus distinguishing from, and affording marked advantages over, the tubular type of element hereinbefore referred to.

Having thus described my invention, what I claim is:

- 50 1. As a new article of manufacture, an electrical heating element consisting of a resistor, a formed sheet metal sheath enveloping said resistor and spaced therefrom, and a mass of granular refractory electrical insulating material of high heat conducting quality filling the space between the resistor and the sheath, the resistor being provided with terminals each accessible through an opening in the sheath.
- 55 2. As a new article of manufacture, an electrical heating element comprising a resistor, a sheet metal sheath made up of a plurality of parts enveloping said resistor and spaced therefrom, and a mass of granular refractory electrical insulating material filling the space between the resistor and sheath, the resistor being provided with terminals each accessible through an opening in the sheath.

60 of high heat conducting quality filling the space between the resistor and sheath, the resistor being provided with terminals each accessible through an opening in the sheath.

65 3. As a new article of manufacture, an electrical heating element consisting of a resistor, a formed sheet metal sheath enveloping said resistor and spaced therefrom, and a mass of granular refractory electrical insulating material filling the space between the resistor and the sheath, the entire assembly being in a highly compacted state, the resistor being provided with terminals each accessible through an opening in the sheath. 70

75 4. As a new article of manufacture, an electrical heating element comprising a resistor arranged in flat formation, a sheet metal sheath made up of a plurality of parts enveloping said resistor and spaced therefrom, and an artificially compacted mass of granular refractory electrical insulating material filling the space between the resistor and sheath, the resistor being provided with terminals each accessible through an opening in the sheath. 80

85 5. As a new article of manufacture, an electrical heating element comprising a resistor arranged in flat formation, a sheet metal sheath made up of a plurality of parts enveloping said resistor and spaced therefrom, and an artificially compacted mass of granular refractory electrical insulating material filling the space between the resistor and sheath, said element having a relatively 90 large area and a relatively thin cross section, the resistor being provided with terminals each accessible through an opening in the sheath. 95

100 6. As a new article of manufacture, an electrical heating element comprising a resistor, a sheet metal sheath made up of a plurality of parts enveloping said resistor and spaced therefrom, and an artificially compacted mass of granular refractory electrical insulating material filling the space between the resistor and sheath, the resistor being provided with terminals each accessible through an opening in the sheath, 105 said element having a relatively large area and a relatively thin cross section, the element being capable of being formed to a shape other than flat. 110

115 7. As a new article of manufacture, an electrical heating element comprising a resistor, a sheet metal sheath made up of a plurality of parts enveloping said resistor and spaced therefrom, and an artificially compacted mass of granular refractory electrical insulating material filling the space between the resistor and sheath, said element having a relatively large area and a relatively thin cross section, the element being capable of being formed to a shape other than flat and the resistor being of sinuous formation and 120 125 130

arranged with its sinus in a plane substantially parallel to that of the relatively large area of the element and being provided with terminals each accessible through an opening in the sheath.

8. As a new article of manufacture, an electrical heating element comprising a resistor, a sheet metal sheath enveloping said resistor and spaced therefrom, the sheath comprised of parts that are held together by the marginal portion of one of said parts being turned over the margin of the other, and an artificially compacted mass of granular refractory electrical insulating material filling the space between the resistor and the sheath, the resistor being provided with terminals each accessible through an opening in the sheath.

9. As a new article of manufacture, an electrical heating element comprising a resistor, a sheet metal sheath made up of a plurality of parts enveloping said resistor and spaced therefrom, and an artificially compacted mass of granular refractory electrical insulating material filling the space between the resistor and sheath, the sheath being closed throughout its periphery by the pressed together edges of the parts thereof, and the resistor being provided with terminals each accessible through an opening in the sheath.

10. As a new article of manufacture, an electrical heating element comprising a resistor, a sheet metal sheath enveloping said resistor and spaced therefrom, the sheath being comprised of an open sided sheet metal receptacle and a cover applied thereto and held to the receptacle by the edge portion of the receptacle being turned over the edge of the cover throughout the periphery thereof, and an artificially compacted mass of granular refractory electrical insulating material filling the space between the resistor and sheath, the resistor being provided with terminals each accessible through an opening in the sheath.

11. As a new article of manufacture, an electrical heating element comprising a sinuous resistor arranged in flat formation, a sheet metal sheath made up of a plurality of parts enveloping said resistor and spaced therefrom, and a mass of granular refractory electrical insulating material of high

heat conducting quality filling the space between the resistor and the sheath, the sheath having a flat working face from which the resistor is uniformly spaced throughout its length, and the resistor being provided with terminals each accessible through an opening in the sheath.

12. An electrical heating element comprising a sheath of sheet metal having a pair of opposed superficial faces of comparatively large area and a pair of faces connecting the former faces that are of comparatively narrow width, the sheath enclosing a shallow cavity, granular refractory electrical insulating material artificially compacted in said cavity, and a sinuous resistor enveloped in the insulating material and the sinus whereof lie in a surface which is parallel to the aforesaid faces of larger area, the resistor being provided with terminals each accessible through an opening in the sheath.

13. As a new article of manufacture, an electrical heating element comprising a resistor, a sheet metal sheath made up of a plurality of parts enveloping said resistor and spaced therefrom, a mass of granular refractory electrical insulating material filling the space between the resistor and sheath, the resistor being provided with terminals each accessible through an opening in the sheath, and means for tying the opposite walls of said sheath together to prevent warping thereof, said means being located within the area of the active surface of the element.

14. As a new article of manufacture, an electrical heating element comprising a resistor, a sheet metal sheath made up of a plurality of parts enveloping said resistor and spaced therefrom, and a mass of granular refractory electrical insulating material filling the space between the resistor and the sheath, the opposite walls of said sheath being tied together through the mass of insulating material and within the area of the active surface of the element, and the resistor being provided with terminals each accessible through an opening in the sheath.

In testimony whereof, I hereunto affix my signature.

EDWIN L. WIEGAND.

DISCLAIMER

1,614,330. *Edwin L. Wiegand*, Dormont Borough, Pa. ELECTRICAL HEATING ELEMENT. Patent dated January 11, 1927. Disclaimer filed November 2, 1938, by the patentee; and the licensee, *Edwin L. Wiegand Company*.

Hereby enter this disclaimer:

A. To so much of claim 1 of said Letters Patent as may cover any electrical heating element in which the sheath surrounding the resistor is not relatively thin and wide in cross section, or does not constitute a surface of relatively large area for the transfer of the heat from the element, or does not define a relatively shallow cavity of relatively small capacity, or in which the resistor is not arranged in a formation correspondingly relatively thin and wide in cross section, or in which the electrical insulating material is not compacted, or in which no part of the electrical insulating material is integrated into formation positively spacing the resistor from the sheath.

B. To so much of claim 3 of said Letters Patent as may cover any electrical heating element in which the sheath surrounding the resistor is not relatively thin and wide in cross section, or does not constitute a surface of relatively large area for the transfer of the heat from the element, or does not define a relatively shallow cavity of relatively small capacity, or in which the resistor is not a resistance conductor arranged in a formation correspondingly relatively thin and wide in cross section, or in which the electrical insulating material is not of high heat conducting quality, or in which the electrical insulating material is not in heat-conduction contact both with all parts of the surface of said conductor over substantially the entire length of said conductor and with all parts of the interior of the sheath surrounding the resistor and adapted to conduct the heat generated in the resistor arranged in said relatively thin and wide formation substantially from all parts of the surface thereof readily and directly to all parts of said relatively large area heat-transfer surface, or in which no part of the electrical insulating material is in integrated condition and disposed in position positively spacing the resistor from the sheath.

C. To so much of claim 5 of said Letters Patent as may cover any electrical heating element in which the electrical insulating material is not of high heat conducting quality, or in which the sheath surrounding the resistor is not relatively thin and wide in cross section, or does not constitute a surface of relatively large area for the transfer of the heat from the element, or does not define a relatively shallow cavity of relatively small capacity, or in which the resistor is not a resistance conductor arranged in a formation correspondingly relatively thin and wide in cross section, or in which the electrical insulating material is not in heat-conduction contact both with all parts of the surface of said conductor over substantially the entire length of said conductor and with all parts of the interior of the sheath surrounding the resistor and adapted to conduct the heat generated in the resistor arranged in said relatively thin and wide formation substantially from all parts of the surface thereof readily and directly to all parts of said relatively large area heat-transfer surface.

D. To so much of claim 12 of said Letters Patent as may cover any electrical heating element in which the electrical insulating material is not of high heat conducting quality, or in which the sheath surrounding the resistor is not relatively thin and wide in cross section, or does not constitute a surface of relatively large area for the transfer of the heat from the element, or does not define a relatively shallow cavity of relatively small capacity, or in which the resistor is not a resistance conductor arranged in a formation correspondingly relatively thin and wide in cross section, or in which the electrical insulating material is not in heat-conduction contact both with all parts of the surface of said conductor over substantially the entire length of said conductor and with all parts of the interior of the sheath surrounding the resistor and adapted to conduct the heat generated in the resistor arranged in said relatively thin and wide formation substantially from all parts of the surface thereof readily and directly to all parts of said relatively large area heat-transfer surface.
